US0D1104289S

(12) United States Design Patent (10) Patent No.: US D1,104,289 S
(45) Date of Patent: * Dec. 2, 2025

(54) MASSAGER

(71) Applicant: Xiaohong Liao, Zhejiang (CN)

(72) Inventor: Xiaohong Liao, Zhejiang (CN)

() Term: 15 Years

(21) Appl. No.: 29/943,672

(22) Filed: May 23, 2024

(30) Foreign Application Priority Data

Feb. 6, 2024 (CN) 202430080980.5

(51) LOC (15) Cl. 24-01

(52) U.S. Cl.

USPC D24/215

(58) Field of Classification Search
